UNITED STATES PATENT OFFICE

2,136,711

DISPATCHER

Arch D. Rollins, Chicago, Ill., assignor, by mesne assignments, to Temporator Company, Chicago, Ill., a corporation of Illinois

Original application October 11, 1926, Serial No. 140,721. Divided and this application October 5, 1934, Serial No. 747,107

6 Claims. (Cl. 177—338)

My invention relates to dispatcher and controlling means for timing and controlling factory operations. One object of my invention is to provide improved factory control means whereby a central station may at all times be informed of conditions in the work in various parts of the factory. Another object is to provide such means whereby by a simple system of signals, a central station may be kept informed as to the specific progress of specific pieces or jobs of work going on through the various parts of the factory. Another object is the provision of a central station, and a plurality of sub-stations in quick and easy communication with the central station, whereby the central station may by signal receive from and impart to the sub-stations necessary information. Other objects will appear from time to time in the course of the specification and claims.

This application is a division of my original application Serial No. 140,721, filed October 11, 1926, now Patent No. 1,976,248 issued October 9, 1934.

I illustrate my invention more or less diagrammatically in the accompanying drawings, where-

in—

Figure 1 is a perspective view of one of the sending or receiving units;

Figure 21 is an elevational view of a system showing a central station or sending set and a plurality of receiving sets;

Figure 22 is a schematic diagram illustrating the electrical connections of a typical system.

Like parts are indicated by like characters throughout the specification and drawings.

It will be understood that I employ a number of sending and receiving units, of which one may be a central station and the others branch stations. The mechanism of the various units are similar, the differences between them being largely in matters of wiring and circuit.

Referring for example to Figures 1, 2, 3, and 4, A generally indicates a base member, herein shown as of sheet metal, consisting of the bottom plate A¹, the upstanding circumferential side wall A², the ledge A³, inwardly projecting therefrom and the flange A⁴ upwardly projecting from the ledge A³. The flange A⁴ is at each end inwardly and then upwardly continued, to form the upstanding wings A⁵.

At each end of the base A is positioned a block B, held in position for example by the screws B¹. In it is rotatably mounted the pin B², provided with a key aperture B³ at its outer end and with a hook element B⁴ at its inner end. B⁵ is any suitable member for preventing axial movement of the pin B², the pin being grooved as at B⁶. The wall A⁴ is cut away as at B⁷ to permit the rotation of the hook B⁴.

Resting upon the ledge A³ and centered by the flange A⁴ is any suitable housing member, generally indicated as C, including a generally vertical rear wall C¹, a short vertical front wall C², a rearwardly inclined forward face C³, a horizontal top C⁴ and end walls C⁵. Positioned in the forward front face C³ is any suitable indexing mechanism, including the fixed stop D and the rotating member D¹ provided with the various apertures D² overlying the fixed indicating symbols D³. D⁴ is a push bottom positioned in the same inclined forward face C³ of the housing and D⁵ is a glass or lens preferably red.

The housing face is forwardly upset as at D⁷ apertured as at D⁸, the upset portion being adapted to receive a pane of glass D⁹ to close such

aperture. D^{10} are headed pins on the inside of the ends of the housing, such pins being adapted to be engaged by the hooks or latches B^4 .

Mounted on the bottom of the base member A 5 is the block E of insulating material upon which are a plurality of contact strips E^1 held for example by the screws E^2 , the block as a whole being held in position by the screws E^3 . Mounted on the inside of the rear wall of the housing are a 10 plurality of holding clips E^5 adapted to receive the contact holding plugs E^6 of insulating material. Mounted in such plugs are the spring pressed plungers or pins E^7 , adapted to engage the contact strips E^1 when the housing is in position on the base. E^8 are any suitable conductors, communicating with the plungers E^7 , which extend to the dial mechanism above described.

Mounted between the upwardly projecting wings A^5 is a supporting structure comprising end 20 plates G , connected by the transverse members G^1 , G^2 riveted or otherwise secured thereto. The member G^1 is flanged at front and rear as at G^3 , G^4 , the lower flange G^4 being substantially shorter than the upper flange. The member G^2 25 is flanged at each edge as at G^5 , G^6 . The flanges G^3 , G^5 , G^6 are notched at intervals as at G^7 , the width of the flanges at the bottom of the notches being substantially equal to the flange G^4 . The end members G are slotted at three points as at 30 G^{10} , these slots overlying the transverse slots G^{11} in the wings A^5 , the intersecting slots permitting adjustment of the relation of the opposed plates. G^{12} are any suitable securing bolts with the nuts G^{14} , the inner washer G^{15} and the outer washer 35 G^{16} , as shown in Figure 19.

Secured to the upper edge of the lower side of the member G^1 are a plurality of blocks H of insulating material apertured to receive a plurality of contact sleeves H^1 which are upwardly 40 slotted as at H^2 , as shown in Figure 17. Each such sleeve has secured at its lower end, as shown in Figure 16, any suitable wire or conductor.

Secured to the lower edge of the rear of the member G^1 are a plurality of blocks H^3 similar 45 to the blocks H and provided with similar slotted contact sleeves H^1 .

Riveted or otherwise secured to the member G^2 adjacent the upper portion of the bottom thereof is the bracket member J , to which is secured the insulating block J^1 , to which are secured the clip and conductor members J^2 , associated with which is a light J^3 , herein shown as a standard telephone light. The light J^3 is 50 centered beneath the glass or lens D^5 , earlier mentioned, and secured adjacent the opposite end of the members G^2 is the similar bracket member J^6 with the insulating block J^7 in which is mounted a double switch comprising three stationary leaves or contacts J^8 , J^9 , J^{10} , between which are located the two movable leaves J^{11} , J^{12} , provided with the insulating spacing members J^{13} , J^{14} . It will be understood that the switch is positioned beneath the switch button D^4 , and that a pressure upon the button D^4 , will move the switch leaves 55 J^{11} , J^{12} .

Secured to the lower face of the member G^2 intermediate the brackets J and J^6 are two identical quick acting magnets K , K^1 , each comprising a bracket member K^2 having an outwardly turned flange K^3 to which is secured a contact block K^4 and the switch bracket K^5 . K^3 , K^4 , K^5 are herein shown as secured together by the screw K^6 , the inner end of which serves also to support and position the magnetic coil K^7 by axial engagement 70 with its core K^8 . Mounted on the switch bracket 75

K^9 of the quick acting magnet K^1 , in which are mounted the switch leaves K^{10} , K^{11} , K^{12} being provided with a terminal insulated block K^{12} , K^{14} are ears projecting outwardly from the switch bracket K^5 . To them is pivoted the switch controlling lever, one arm of which K^{15} is adapted to engage the block K^{12} on the leaf K^{10} , and the other arm of which K^{16} is adapted to be drawn to the core K^8 of the electromagnetic coil K^7 in response to its electric actuation. The leaf K^{10} is 10 in such case thrust into contact with the leaf K^{11} , the switch being thus closed in response to and during actuation of the electromagnetic coil K^7 . The magnet K has mounted on the insulating block K^9 the switch leaves K^{20} , K^{21} (Fig. 7). 15

Secured to the opposite side of the member G^2 , adjacent one end thereof, is the insulating block L (Fig. 12), held for example by the screws L^1 , and provided with nine contact sleeves L^2 substantially identical with the contact sleeves H^1 earlier 20 described. This is shown particularly in Figures 6, 7 and 12.

Secured to one of the end plates G of the cradle, for example as shown in Figures 3, 5 and 6, is a bracket member M mounted upon the 25 flange M^1 inwardly projecting from the plate G . The bracket carries the electro-magnet M^2 with the core M^3 . M^4 is a reset shaft rotatably mounted in the plates G and extending from end to end of the cradle, it being held at the ends for example by the screws M^5 passing through the plates G . Mounted thereupon is the arm M^6 and the plate M^7 opposed to the core M^3 of the electro-magnet. It is to be understood that actuation of the electro-magnet will draw the arm 30 M^6 toward the core M^3 , and thus rock the shaft M^4 . M^8 indicates a stop member with the terminal lug or hanger M^9 adapted to limit the downward movement of the lever M^6 when it drops in response to gravity during inactivity of 40 the magnet. It will be understood that the reset shaft M^4 carries a plurality of levers M^{10} , arranged to cooperate, respectively, with the locking pawl levers O^3 , hereinafter referred to, for the purpose of simultaneously releasing all of 45 said pawls when the shaft is rocked due to energization of magnet M^2 . Furthermore, the said levers M^{10} may be adjusted and positioned as a group, with respect to said locking pawl lever, by slightly depressing or by bending the flange M^9 50 of the stop M^8 .

Mounted upon the members G^1 , G^2 , and seating in the slots G^7 , are a plurality of indicator units and a single advance unit. The indicator units are identical and but one will be described. Each 55 such indicator unit, shown in detail for example in Figures 8, 9 and 10, consists of a side plate N with a forward flange N^1 at right angles thereto and an upper flange N^2 likewise at right angles to the plate. The side flanges N^1 and N^2 thus 60 partially enclose the mechanism mounted on the plate N , and they are so shaped and proportioned that when several units are assembled in juxtaposed position on the cradle unit, said flange cooperates with the exposed face of the next adjacent unit, to aid mounting the proper relative positions of the several units on said cradle structure, and more particularly with respect to the windows in the face plate through which the indicating characters are visible. Mounted 65 upon the flange N^2 is the bracket N^3 carrying the electro-magnetic coil N^4 with its core N^5 . It also carries the insulating block N^6 carrying three contact pins N^7 adapted to engage the contact sleeves H^1 in the block H . It is to be further 70 75 80 85 90 95

noted that the side plate of each unit is cut away at N^{23} to permit the units to straddle the reset shaft M^4 as shown in Figures 8 and 9.

Pivoted to the plate N , as at N^8 , is the lever N^9 , having a portion N^{10} opposed to the core N^5 of the electro-magnet. At the lower end of the lower arm of the lever is pivoted, as at N^{11} , a supplemental lever having an upper arm N^{12} and a lower arm N^{13} having a rocking or cam surface N^{14} opposed to a lug N^{15} on the plate N . The upper arm of the lever N^{12} is normally moved to the right, as shown in Figure 9, by the tension spring N^{16} . It carries a dog N^{17} normally moved in clockwise direction by the spiral spring N^{18} against the guide or stop N^{19} . N^{20} is a stop to limit the movement of the dog. N^{22} is a stop on the plate N to limit the turning of lever N^9 .

O is a shaft fixed upon the plate N upon which is mounted a sleeve O^1 to which is fixed a ratchet wheel O^2 . Counter-clockwise direction of rotation of the sleeve and ratchet wheel is prevented by the pawl O^3 pivoted as at O^4 to the plate and normally held in operating position by the tension spring O^5 . It will be understood that at each actuation of the electro-magnet N^4 the number N^{10} will be drawn to the core N^5 and the lower arm of the lever N^9 will be rotated clockwise, as shown in Figure 9, the lever arm N^{13} will engage the stop N^{15} and rotate about the pivot N^{11} . The dog N^{17} will be thrust along the guide N^{19} to engage the ratchet teeth of the wheel O^2 , imparting to the wheel and sleeve O^1 a movement in clockwise direction. The stop N^{20} limits this movement to a distance substantially equal to the length of one of the ratchet teeth, the pawl O^3 overriding one tooth and engaging the next tooth to prevent rotation of the sleeve in the opposite direction. It will be understood that the reset shaft M^4 with its lever M^{10} will, upon its counter-clockwise rotation as shown in Figure 9, move the pawl O^3 into inoperative position, thereby releasing the ratchet wheel and permitting retrograde rotation of the sleeve O^1 .

The sleeve O^1 , as shown in Figure 9, the control of the rotation of which has above been described, carries the following indicator mechanism. P , P^1 are cupped wheels with the outwardly turned rims or flanges P^2 , upon which is positioned the indicator strip P^3 . P^4 is a stop element associated with the wheels P , P^1 and adapted to engage the fixed stop P^5 on the plate N at the limit of rotation of the wheels. The stop P^4 also engages the insulating block P^6 on the end of the "off normal" switch leaf P^7 mounted in the insulating block P^8 . Referring to Figure 10, when the stop P^4 is engaging the fixed stop P^5 , and prior to rotation of the indicating assembly, it is in engagement with said block P^6 and is holding the switch leaf P^7 out of contact with the opposite switch leaf P^9 . As soon as the assembly is rotated from normal position and as soon as the stop P^4 clears the block P^6 , the "off normal" switch is closed and remains closed until the said stop returns to its initial position. The squared portion O^{10} of the shaft O carries the plate P^{10} , thereby fixed against rotation. Between the plate P^{10} and the sleeve O^1 is the spiral spring P^{11} adapted normally to rotate the sleeve O^1 in counter-clockwise direction, as shown in Figs. 9 and 11, this tendency being normally checked by the interposition of the pawl O^3 . P^{12} is a pin which passes through the wheels P , P^1 , the stop P^4 and the ratchet wheel O^2 , and through flanges O^{11} , O^{12} on the sleeve O^1 , thus holding the entire assembly against relative rotation.

It will be understood that the indicator member P^3 may be provided with any desired symbols, the indicator strip and the wheels upon which it is mounted being aligned with the glass D^7 , the forward flanges N^1 of the plate N being cut away as at N^{21} to render the signals visible.

Figures 12, 13 and 14 illustrate the advance unit adapted to control the advance or movement of the successive individual indicator units, in response for example to dialing. The advance units include a frame structure substantially identical with that of the indicator units, including the side plate N with the forward flange N^1 at right angles to it, and the upper flange N^2 also at right angles to the plate. The same bracket N^3 carries an identical electro-magnetic coil R with its core R^1 and the insulating block R^2 with the three contact pins on each side adapted to engage the contact sleeves H^1 in one of the blocks H .

Similarly, the lever N^9 is pivoted as at N^8 to the plate N and supports a portion N^{10} opposed to the core R^1 of the electro-magnet. The lower end of the lever has pivoted to it, as at N^{11} , the supplemental lever with the upper arm N^{12} and the lower arm N^{13} with its rocking or cam surface N^{14} opposed to the lug N^{15} on the plate. The upper arm N^{12} is normally moved to the right, as shown in Figure 12, by the tension spring N^{16} and carries the dog N^{17} .

S is a shaft secured to the plate N and S^1 is a reduced shaft portion forwardly extending from the end of the thicker portion of the shaft. The reduced portion is squared at the end as at S^2 and provided with a lock spring clip S^3 .

Surrounding the shaft S , S^1 is the sleeve S^4 conforming thereto. Mounted about that portion of the sleeve which surrounds the thicker portion S of the shaft is the ratchet wheel S^5 , the spacers S^6 , the stop members S^7 adapted to engage the fixed stop P^5 on the plate N , and the indicator discs S^8 with the indicator strip S^9 , the structure being substantially the same as that shown in Figure 11 and employed for the individual indicator units.

The portion of the sleeve S^4 which surrounds the reduced portion S^1 of the shaft carries a number of elements below described and terminates in a squared portion S^{10} upon which is mounted a disc S^{11} surrounded by the spring S^{12} , the inner end of the spring penetrating a slot S^{14} of the disc and the outer end being secured to the member S^{15} inwardly projecting from the wheel S^{16} fixed on the square portion S^2 of the shaft S and held in position by the spring lock member S^3 . The stop member S^7 is adapted to engage the fixed stop P^5 on the plate N and to actuate the switch levers S^{18} , S^{19} identically as the stop member P^4 actuates switch levers P^7 and P^9 .

The parts above described are substantially identical in form and operation to the corresponding parts shown in Figure 11 and found in the individual indicator units.

Mounted on the lower portion of the shelf N^2 is the sheet metal bracket T to which is secured the block T^1 of insulating material centrally apertured as at T^2 to permit the passage of the reduced portion of the sleeve S^4 . Secured to the outer face of the block T^1 are the shield members T^3 , T^4 positioned back to back, as shown in Figure 13, the outer rim T^5 of the member T^4 extending outwardly around and surrounding the spring S^{12} .

Mounted on the block T^1 concentrically about the central aperture T^2 is the contact ring T^6 .

- secured for example by the screws T^7 and having the outwardly projecting rim or flange T^8 . Mounted concentrically about it are a plurality of contacts T^9 , each including the hollow sleeve T^5 .
5. T^{10} passing through the block T^4 , the outwardly projecting portion T^{11} and the inwardly turned portion T^{12} . T^{14} is any suitable wiring connection extending from such contacts to the contact pins T^{15} in the block T^{16} secured to the bracket T (Fig. 12). It will be understood that there is a pin and a wiring connection for each of the indicator units.

10. Mounted about the reduced portion of the sleeve S^4 are any suitable insulating rings U , held in position by the locking member U^1 and having mounted thereupon three wipers U^2 , U^3 , U^4 . The wiper U^2 is adapted to wipe the outer face of the flange T^8 . U^3 and U^4 wipe the opposite sides of the inwardly turned portions T^{12} of the contact member T^9 .

15. Referring to Figure 20, which is a modified form of the operation of the structure shown for example in Figures 8 and 9, the upper arm N^{12} of the supplemental lever pivoted to the lower end of the lever N^9 , has pivoted to it a dog N^{25} having an upwardly extending ear N^{26} to which is secured the single tension spring N^{27} which carries out the function of both of the springs N^{16} and N^{18} , as shown in Figure 9, drawing the lever arm to the right and imparting a clockwise movement to the dog N^{25} .

20. As illustrated in Figure 15, the indexing device has at the rear a plurality of spring contacts insulated from each other, of which two V^1 , V^2 are operated by the cam V^3 , which in turn is actuated by the turning of the rotating member D^1 . The cam V^3 is positioned so as to hold the spring contacts V^1 , V^2 apart when the indexing device is at rest. The spring contacts V^4 , V^5 are closed and opened by the lever V^6 in the usual manner. The spring contacts V^2 and V^5 are electrically connected as at V^7 .

25. Figure 21 illustrates a schematic layout of a central station and sub-stations, of which three are shown.

30. W indicates a switch-board panel of insulating material. Mounted thereon are a plurality of multiple jacks W^1 and pilot lights W^2 , each pair representing a different sub-station which may be identified by numbers, as shown. Secured to each jack W^1 are a plurality of wires, later to be described and generally indicated as W^3 , which extend to the sub-stations x .

35. Y is the control station having a phone plug Y^1 connected to the wire cord Y^2 .

40. The use and operation of my invention are as follows:

45. One of the objects of my invention being to provide improved factory control means whereby a central station may at all times follow up the work in various parts of the factory, and whereby means of communication between a central station and sub-stations are provided, I have developed a system whereby from a plurality of sending stations information may be sent to a central receiving station, it being understood that the receiving station can send and the sending stations can receive. I thus provide a complete system of factory communication. The general 50 operation of the device will be clear from Figure 22, a schematic layout or wiring diagram in which only two stations are shown, one of which may be considered the main receiving or central station and the other, one of the supplemental stations.

5. In practice, each station includes a receiving and sending mechanism, housed as shown for example in Figures 1 and 2 and 21, with a dialing mechanism on the forward face of the housing C and a transparent window adapted to permit the observation of one symbol at a time upon each of the plurality of indicating cylinders or strips employed.

10. When an operator wishes to send a message from any of the sub-stations, he presses the button D^4 which actuates the switch leaves J^{11} , J^{12} . The effect is to close the circuit through the pilot light W^2 on the switch-board W , along the conductive line d from the battery d^1 along the conductor d^2 , the light W^2 and line d^3 , through the leaves J^9 , J^{11} back along the conductor d^4 and back through d^5 to the battery d^1 . The light W^2 is preferably positioned only at the central station switch-board and serves to indicate that an operator at a sub-station is trying to communicate. 15 The central operator then takes the plug Y^1 , which may be a regular telephone plug connected to the central station, and plugs it into the multiple jack W^1 , thereby closing the circuit through the line d from the battery d^1 , the jack W^1 , line e , 20 wire e^1 through the light J^3 showing through the red lens D^6 on the face of the sub-station X , the wire e^2 , spring leaves J^8 , J^{11} , back through the wire d^3 , the jack W^1 , wires e^3 , d^5 to the battery d^1 . At the same time the circuit is closed through 25 the pilot light W^2 , independently of the closure of the manually operated switch button D^4 , the circuit being made from the battery d^1 through the wires d , d^2 , pilot light W^2 , wire d^3 , the jack W^1 , lines e^3 , d^5 back to the battery. At the same 30 time the sub-station and the main station are so connected that any actuation of the dial of the sub-station will actuate the identical indicating members and actuate the advance units of the two stations identically so that identical signals 35 will appear at both stations, thus enabling the sender to check his message.

40. Accordingly when the light J^3 is illuminated, the sender, knowing that the connection has been made, proceeds to dial his message by actuating the rotating member D^1 with its apertures D^2 overlying the fixed indicating symbols D^3 . The operator places his finger in the aperture over the desired number or letter to be indicated and rotates the member D^1 until his finger engages the stop D . The operation of this mechanism being the same as that commonly employed in that of automatic telephones, I have made no detailed description of this feature.

45. By rotating the member D^1 in clockwise direction, the arm V^6 moves out of contact with the leaf spring V^4 , thereby closing the contact leaves V^4 , V^5 and making electrical connection through the relay coils K^1 of the station X and coil K^1 of the central station Y . A circuit is 50 established from the battery d^1 through the line d , multiple jack W^1 , line e , wire f , the relay magnet K^1 , wire f^1 , f^2 , the spring leaf contacts V^4 , V^5 of the sub-station indexing dial, lines f^3 , d^4 , d^5 back to the battery d^1 . Electrical connection is also made from the battery d^1 through the wires d , f^4 , the relay magnet K^1 of the central station Y , lines f^5 , f^6 , the switch-board jack W^1 , lines f^7 , f^8 , contact leaves V^4 , V^5 , lines f^9 , d^4 , d^8 back to the battery d^1 . Magnetizing of relay coil 55 K^1 causes switch leaves K^{10} , K^{11} to be closed, thereby establishing an electrical circuit from the battery d^1 , wire d , switchboard jack W^1 , wires e , f , contact leaves K^{11} , K^{10} , the line g , magnet R , lines g^1 , d^5 and back to the battery. Through 60 K^{11} causes switch leaves K^{12} , K^{13} to be closed, thereby establishing an electrical circuit from the battery d^1 , wire d , switchboard jack W^1 , wires e , f , contact leaves K^{13} , K^{12} , the line g , magnet R , lines g^2 , d^5 and back to the battery. Through 65 K^{13} causes switch leaves K^{14} , K^{15} to be closed, thereby establishing an electrical circuit from the battery d^1 , wire d , switchboard jack W^1 , wires e , f , contact leaves K^{15} , K^{14} , the line g , magnet R , lines g^3 , d^5 and back to the battery. Through 70 K^{15} causes switch leaves K^{16} , K^{17} to be closed, thereby establishing an electrical circuit from the battery d^1 , wire d , switchboard jack W^1 , wires e , f , contact leaves K^{17} , K^{16} , the line g , magnet R , lines g^4 , d^5 and back to the battery. Through 75 K^{17} causes switch leaves K^{18} , K^{19} to be closed, thereby establishing an electrical circuit from the battery d^1 , wire d , switchboard jack W^1 , wires e , f , contact leaves K^{19} , K^{18} , the line g , magnet R , lines g^5 , d^5 and back to the battery.

this impulse the magnet R attracts the upper portion N¹⁰ of the lever N⁹, which actuates the arms N¹², which by its rocking motion of its cam surface N¹⁴ of the lower portion N¹³ against the lug N¹⁵ moves the dog N¹⁷ to the left, thereby engaging a tooth of the ratchet wheel S⁵ and turning the sleeve S⁴ in clockwise direction. As soon as the assembly is rotated and as soon as the stop S⁷ clears the switch contacts S¹⁸, S¹⁹, the switch is closed and establishes an electrical circuit, which will be later described.

By turning of the sleeve S⁴, the wipers U³, U⁴, are moved into contact with a contact sleeve T⁹, thereby establishing an electrical connection 15 through the magnet N⁴ of the indicator unit farthest to the left. Through magnetizing of the relay coil k¹ of the central station, the contact leaves k¹⁰, k¹¹ are closed and thereby establish a circuit from the battery d¹, wires d, f⁴, 20 contact leaves k¹⁰, k¹¹, wire g³, the magnet coil r of the advance unit of the central station Y, wires g⁴, g⁵, d⁵ and back to the battery. Through this electrical impulse, the magnet r of the advance unit of the central station causes the 25 switch leaves s¹⁹, s¹⁸ to be closed and moves wiper U⁴ into contact with a contact sleeve t⁹, connected by the line i³ with the magnet n⁴ of the indicator unit farthest to the left. By the closing of the switch leaves s¹⁹, s¹⁸ electrical connection is made from the battery d¹ through the 30 wires d, f⁴, g⁶, the red light j³⁰ of the central station Y, wire g⁷, contact leaves s¹⁸, s¹⁹, wires g⁸, g⁴, g⁵, d⁵ back to the battery.

As soon as the operator of the substation X 35 allows the rotating member D¹ of the dial to return to its original position, the cam V³ rotates and closes and opens contact leaves V¹, V² as many times as the number dialed. Electrical circuits are thereby made from the battery d¹, 40 wire d, jack w¹, wire e, relay magnet K of the substation X, wires h, h¹, contact leaves V¹, V² of the dial, wires f³, d⁴, d⁵ back to the battery, and another circuit from the battery d¹ through the wires d, f⁴, h², relay contacts k²⁰, k²¹, wire 45 i², wiper u⁴ of the advance unit of the central station Y, wire i³, magnet n⁴, wires g⁴, g⁵, d⁵ and back to the battery. As soon as the dial at X station is moved by the operator into the off-normal or operative position, negative battery is 50 fed through d⁵, d⁴, f³ through the dial contact V⁵ into dial leaf spring V⁴, thence through f², f¹, energizing K¹. The current divides between f¹ and f², and also travels through f¹ through jack W¹ along the lines f⁶, f⁵, to energize the 55 electromagnet K¹, thence through the lines f⁴ and d to the battery. Likewise the energy returns from K¹ through f, through e, through jack W¹ to wire d, to positive battery. It is seen, therefore, that K¹, k¹ are energized simultaneously and 60 are in parallel. Likewise, dial Z is wired in parallel with the dial at station X, through f⁷ and f⁶. Also g⁵ supplies negative battery to dial Z. Likewise d⁵, d⁴, f³ supplies direct negative battery to dial at station X.

65 When the cam V³ on either dial X or Z is rotated a number of times predetermined by the digit dial, the contact springs V¹ and V² close. V² receives negative battery through d⁵, d⁴, f³ and supplies negative battery to V¹, thence through h¹, wherein the current divides into h and h². The current passing through h energizes relay magnet coil K, returning to battery through f, through d, to positive battery. Likewise h² through jack W¹ through h⁵, h⁴ in the

plug Y¹ through h³, thence to k relay magnet, thence through h², f⁴ to positive battery d¹.

Thus relay magnets K, k receive impulses from either dial X or Z which cause these relays in turn to supply impulses from positive 5 battery through d, through jack W¹, through e, also from positive battery through wires f⁴, h² through contacts K²¹ and k²¹, thence through contacts on armature of relay K²⁰ and k²⁰, through i² and i, thence through wiper arm U⁴, 10 u⁴ on each advance unit through the wire i³, i¹ on each station X and Y, through the indicator unit magnet N⁴, n⁴ to negative battery through g¹, d⁵ and g⁴, g⁵ and d⁵.

The so-called reset magnets M², m² are operated in parallel any time that the buttons m⁴ and D⁴ are depressed. The leaf springs m⁵ and J⁹, j¹¹ receive energy as described above. This parallel operation of electromagnets M² and m² only occurs when the plug with the cord attached is inserted in jack W¹, since the wire and contact j⁸, j⁷ through J⁸, j⁹ provides the paralleling of the electromagnets M², m² as herein set forth. Likewise the wire j⁵ leading to plug contact j⁶.

Magnetizing of the magnet coils N⁴, n⁴ causes 15 the switch leaves P⁷, P⁹ of the substation X and the contact leaves p⁷, p⁹ of the central station Y to be closed, thereby establishing two signal circuits, one through the pilot light W², which will 20 be later described, and another through the light J³⁰ of the central station.

Each successive dialing will advance wipers U⁴, 25 u⁴ to the next following contact sleeves T⁹, t⁹, each of which is connected by a wire i¹ or i³ with a magnet N⁴ or n⁴ of an indicator unit, as shown 30 in Fig. 22.

Should the operator of the substation X desire to correct a message, by pressing of the push button D⁴ electrical circuits are made through the reset magnets M², m² of both stations, one circuit 40 from the battery d¹ through the wire d, jack W¹, wires e, j¹, reset magnet M² of the substation X, wire j², switch leaves J¹⁰, J¹², wires d⁴, d⁵ and back to the battery. Another circuit from the battery d¹ through the wires d, f⁴, j³, reset magnet m² of 45 the central station Y, wires j⁴, j⁵, contact j⁶ of the telephone plug Y¹, spring contact j⁷ of the jack W¹, wire j⁸, through the jack W¹, wires j⁹, j², spring contact J¹⁰, J¹², wires d⁴, d⁵ back to the battery.

After receiving of the message, the operator of 50 the central station presses next the push button m⁴ of the receiving and sending device, thereby closing a switch, generally indicated as m⁵. This switch is similar in construction to the one employed at the substation, but has only two spring 55 leaves. By closing of the switch m⁵, electrical circuits are made, one from the battery d¹ through the wires d, f⁴, j³, reset magnet m², wire j⁴, reset switch m⁵, wires m⁶, g⁵, d⁵ and back to the battery. Another circuit from the battery d¹ through the 60 wire d, jack W¹, wires e, j¹, reset magnet M², wire j⁹, jack W¹, wire j⁸, spring contact j⁷ of the jack, contact j⁶ of the plug Y¹, line j⁵, reset switch m⁵, wires m⁶, g⁵, d⁵ back to the battery.

After resetting the station, operator of the central station pulls out the plug Y¹. Should any of the indicator units or advance unit of a substation fail to function properly and any of the spring contacts P⁷, P⁹, or S¹⁸, S¹⁹ keep in contact with each other, the pilot light W² will stay alight, 70 being in circuit with the battery d¹ through the wires d, d², pilot light W², wires d⁴, m¹⁰, spring leaves P⁹, P⁷ or S¹⁸, S¹⁹, wires m¹¹, g¹, d⁵ and back to the battery.

The equipment is laid out in such a manner 75

that any one of the various outlying stations X terminates upon an individual line jack W^1 . By inserting the plug Y^1 in any of the jacks w^1 , the central station receiving and recording equipment is connected to any of the X stations as desired, so that a message may be transmitted from any outlying station to the central station. Likewise, a message can be transmitted from the central station to any outlying station.

10 I claim:

1. In a station for a dispatcher system, a supporting structure, a plurality of indicator units, means for removably mounting the units on said supporting structure, each of said units including an indicating wheel biased to normal non-indicating position, means for advancing said wheel, means for locking said wheels in advanced positions, and reset means for the wheels including a reset shaft mounted in the supporting structure and common to all said wheels, separate lever arms on the shaft for each wheel, and means for rocking the shaft to simultaneously clear all the wheels.

2. In a station for a dispatcher system, a supporting structure, a plurality of indicator units, means for removably mounting said units on said structure, each of said units including an indicating wheel biased to a non-indicating normal position, means for separately advancing said wheels, means for locking the wheels in advanced positions, and means for resetting the wheels to a normal position including a shaft carried by the supporting structure and common to all the units, separate wheel release means for each wheel carried by the shaft, an actuating arm carried by said shaft, and means cooperating therewith to define the normal inoperative position of all of said wheel releasing means.

3. In a station for a dispatcher system, a supporting structure, a plurality of indicator units, means for removably mounting said units on said structure, each of said units including an indicating wheel biased to a non-indicating normal position, means for separately advancing said wheels, means for locking the wheels in advanced positions, and means for resetting the wheels to a normal position including a shaft carried by the supporting structure and common to all the units,

separate wheel release means for each wheel carried by the shaft, an actuating arm including an armature, a magnet carried by said supporting structure and operably positioned with respect to the armature, means for defining the position of the armature when the magnet is deenergized to thereby position all of said arms with respect to the respective units, and means for energizing the magnet to simultaneously clear all the wheels.

4. In a station for a dispatcher system, a supporting structure, a plurality of indicator units, means for removably mounting said units on the supporting structure, each of said units including a side plate having mounted thereon an indicating wheel biased to normal non-indicating position, means for advancing the wheel, and means for locking the wheel in advanced position; a reset shaft mounted in a supporting structure and extending transversely of all of said units, the side plates of said units being cut away in transverse alignment to straddlingly engage said shaft, and means carried by the shaft for simultaneously releasing all of the wheel locking means when the shaft is rocked.

5. In a station for a dispatcher system, a supporting structure, a plurality of indicator units, means for removably mounting said units thereon, each of said units including a side plate, and indicating mechanism mounted thereon, said side plates being provided with flanges at the edges thereof, said flanges extending substantially perpendicularly to the plate to partially enclose the indicator mechanisms mounted thereon.

6. In a station for a dispatcher system, a supporting structure, a plurality of indicator units, means for removably mounting said units thereon, each of said units including a side plate, and indicating mechanism mounted thereon, said side plates being provided with flanges at the edges thereof, said flanges extending substantially perpendicularly to the plate to partially enclose the indicator mechanisms mounted thereon, and being dimensioned to contact the outer face of the side plate of the next adjacent unit when assembled on said supporting structure to insure proper relative positioning of said units.

ARCH D. ROLLINS.
